Primary Examiner — Philip S Hyder*Assistant Examiner* — Ramzi Almatrahi(74) *Attorney, Agent, or Firm* — Michael Best & Friedrich LLP(57) **CLAIM**

We claim the ornamental design for a security camera, as shown and described.

DESCRIPTION

FIG. 1 is a perspective view of a security camera.

FIG. 2 is a side view of the security camera of FIG. 1.

FIG. 3 is an opposite side view of the security camera of FIG. 1.

FIG. 4 is a front view of the security camera of FIG. 1.

FIG. 5 is a rear view of the security camera of FIG. 1.

FIG. 6 is a top view of the security camera of FIG. 1; and, FIG. 7 is a bottom view of the security camera of FIG. 1. The broken lines depict portions of the security camera in which the design is embodied that form no part of the claimed design. Additionally, the dash-dot lines denote the boundary of the claim and form no part of the claimed design.

1 Claim, 6 Drawing Sheets(56)
